UNITED STATES PATENT OFFICE.

CHARLES S. PHILIPS, OF BROOKLYN, NEW YORK.

APPARATUS FOR CURING AND SWEATING TOBACCO.

SPECIFICATION forming part of Letters Patent No. 234,329, dated November 9, 1880.

Application filed April 23, 1880. (No model.)

To all whom it may concern:

Be it known that I, CHARLES S. PHILIPS, of Brooklyn, in the county of Kings and State of New York, have invented a new and Improved Apparatus for Curing and Sweating Tobacco to Dark Colors, of which the following is a specification.

Figure 1 is a sectional elevation of the apparatus. Fig. 2 is a front sectional elevation taken through the line *xx*, Fig. 1.

Similar letters of reference indicate corresponding parts.

The object of this invention is to furnish an improved apparatus or sweat-house for curing and sweating tobacco to dark colors without developing any unpleasant or empyreumatic odors, which is unavoidable when the curing and sweating are done in the ordinary manner.

A is a box or chamber of sufficient size to receive a package or case, B, of tobacco. The chamber A is made with an open bottom and front and with an inclined roof, so that the water of condensation will flow along the under surface of the inclined roof and down the sides and ends of the chamber back into the pan. To the inner surface of the sides and ends of the chamber A are attached upright cleats C, to prevent the case B from getting so close to the said sides and ends as to impede the free circulation of the moist air all around the case B. D is the door, which fits snugly against the forward edges of the sides and top of the chamber A, and has half-keepers E attached to it to receive the fastening-levers F. The levers F are hinged to the forward ends of screw-rods G, which screw into nuts H attached to the sides and top of the chamber A, so that the levers can be readily adjusted to fasten the door D closely.

To the door D is attached a thermometer, I, the bulb of which passes through or is inserted in a hole in the said door, so that the temperature of the chamber A can be ascertained at any time.

The case B stands upon a floor or platform, J, which is slotted or made of slats, so that the moist atmosphere may pass through it freely.

If desired, rollers K may be interposed between the case B and the floor J, for conven-

ience in handling the said case and to allow the moist air to circulate freely around it.

The lower edges of the door D and of the sides and end of the chamber A rest upon the inclined ends and sides of the hopper L, to the lower side of which is attached the metallic pan M that receives the water. By this construction the water of condensation that flows down the sides of the chamber A will flow down the inclined sides of the hopper L. The ends of the cross-bars that support and connect the slats of the floor or platform J rest upon the sides of the hopper L, so that the said platform will not interfere with the free circulation of the moist air.

The pan M is supplied with water through a pipe, N, from a reservoir or tank, O, placed upon a stand, P, or other support, to bring it to a higher level than the pan M, so that the water will flow from it into the pan M as soon as the valve Q in the pipe N is opened.

To the handle of the valve Q is pivoted the upper end of a connecting-rod, R, the other end of which is pivoted to the end of the lever S. The lever S passes through the frame that supports the apparatus and through the side of the pan M, and is pivoted to the side of the pan M, and to its other end is attached a float, T, so that as the water in the pan M rises to the water-line the rise of the float T closes the valve Q and shuts off the water. As the water in the pan M sinks below the water-line the descent of the float T opens the valve Q and admits the water, so that the water in the pan M will be kept at the same level automatically.

The hopper L rests upon a frame, U, which is extended to the rear, so that the chamber A can be slid back out of the way when the case B is to be placed upon or removed from the platform J. To the rear end of the pan M is attached a pipe, V, which projects, and has a cup, W, attached to its outer end, so that the attendant can see at a glance how much water there may be in the said pan M.

The pan M and the water contained in it may be heated by a gas-stove, an oil-stove, or a furnace placed beneath it, or by a coil of steam-pipe placed within it, as may be desired or convenient.

When tobacco is subjected to a moist heat

at a high temperature to produce dark-colored tobacco from light-colored leaves a partial decomposition takes place and a disagreeable empyreumatic odor is given off, which odor 5 can be neutralized or prevented by the application of ammonia to the tobacco during the process of sweating.

In applying this apparatus to practical use the tobacco is wet and is packed in the case 10 B, which may be the original case in which the tobacco was received, or a case made expressly for use in the chamber A, or any case of suitable size, and the cover of the case is fastened on. The case B is then placed in the 15 chamber A, the door D is closed, water is admitted into the pan M, and heat is applied to raise the temperature to the required point. To the water in which the tobacco is wet I add ammonia in the proportion of one pound 20 of ammonia to eight or ten gallons of water; but the proportional quantity of ammonia must be varied as the character of the tobacco may require. The wilder and ranker the tobacco the more ammonia will be required.

25 If, upon examining the tobacco at the end of the third or fourth day of its being operated upon, it is found that the ammonia used in wetting the tobacco has been exhausted, and that it is necessary to continue the sweating,

ammonia is placed in the tank O, that supplies 30 the pan M with water, and ammonia gas will be given off as soon as the water becomes heated, so that the sweating may be continued for any necessary length of time without the diffusion of any unpleasant odors.

35 The process of maturing tobacco which consists in subjecting the same in a dampened condition and in an inclosing-vessel to a heating-bath at less than 212° Fahrenheit temperature is not claimed herein, but is embraced 40 in another pending application filed by me under date of August 2, 1879.

Having thus described my invention, I claim as new and desire to secure by Letters Patent—

45 In an apparatus for sweating and curing tobacco, the combination, with the water-pan M, arranged under sweating-chamber A and platform J, of the hopper L and its supporting-frame U, whereby the water-pan is supported 50 above the floor to form space for an independent heating apparatus, while keeping the platform so low that the case of tobacco can be easily entered and removed.

CHARLES S. PHILIPS.
